Patented June 25, 1918.

Inventor
Frank William Syred

UNITED STATES PATENT OFFICE.

FRANK WILLIAM SYRED, OF HIGH WYCOMBE, ENGLAND.

EXPANDING TABLE.

1,270,458.

Specification of Letters Patent. Patented June 25, 1918.

Application filed July 23, 1917. Serial No. 183,196.

To all whom it may concern:

Be it known that I, FRANK WILLIAM SYRED, a subject of the King of Great Britain and Ireland, residing at High Wycombe, 5 in the county of Buckingham, England, have invented certain new and useful Improvements in Expanding Tables; and I do hereby declare the following to be a full, clear, and exact description of the invention, 10 such as will enable others skilled in the art to which it appertains to make and use the same.

This invention relates to expanding tables and has for its object to so construct a table 15 of the class in question that a loose leaf or flap is automatically raised, so that it becomes level or flush with the table top proper, by simply pulling the two ends of the said top outward, while by reversing the 20 process, the flap is caused to pass down, into a place formed for its reception underneath the table top proper.

And in order that my said invention may be clearly understood, I will describe the 25 same with reference to the drawing accompanying this specification, which shows, by way of example, one form of expanding table with my said invention applied thereto.

Figure 1 is a side elevation of the table 30 closed.

Fig. 2 is an elevation illustrating the construction of the side rails.

Fig. 3 is a side elevation illustrating the first movement to open the table.

35 Fig. 4 is a similar view illustrating the second movement with the flap raised at one side flush with the top of the table.

Fig. 5 is a similar view with the table open and ready for use.

40 Fig. 6 is an end elevation and part section, the section being taken in a vertical plane through the center of Fig. 1 at the place where the top members *a* and *a.1* come into contact.

45 The same letters of reference are employed to denote the same parts in all the views.

a and *a.1* are the top portions of the table, which are provided along each side with 50 slides *b* having rabbets corresponding with grooves in the legs *h* and side rails *g* see Figs. 5 and 6. Attached to the underside of the portion *a* of the table top are the ends of two sliding pieces or runners *c*. These 55 runners are supported and guided upon a bridge *d* under the opposite end *a.1* of the

table. Each of the runners *c* is provided with a cut away portion of sufficient size to enable the flap *e* to rest in the same, when lying beneath the top of the table.

60 Each of the side rails *g* has also a corresponding portion *j* cut away for the same purpose.

The end of each of the runners *c* remote from the top *a* is formed with beveled or 65 sloping portions *i* and the runners *c* are of such dimensions that when the top *a* of the table is pulled out the sloping portions *i* of the runners come beneath the loose leaf and raise one side thereof to a level with the 70 top of the table.

The ends of the cut away recesses in the side rails *g* are also sloped or beveled off at *j*, such bevels facing the bevels *l* on the runners *c* for the purposes hereinafter mentioned. *k* are blocks attached to the underside of the leaf *e* to prevent lateral displacement of the said leaf.

75 The operation of raising and lowering the leaf *e* will be readily understood.

In order to extend the table the portion *a.1* of the top is pulled in an outward direction until it comes into the position shown at Fig. 3, suitable stops being provided for preventing it being pulled too far. Then 80 the other portion of the top is pulled out in the same manner. This movement brings the runners *c* into action, causing the flap *e* to be raised by the bevels *i* as shown at Fig. 4. At the same time, it will be observed 85 that the bevels *f* on the side rails *g* are uncovered. The top *a.1* is now pushed inward causing the leaf to pass up the bevels *f* thus bringing it level with the top of the table as shown at Fig. 5.

90 By these movements of the two portions of the table top, the extended table is ready for use.

In order to close the table, the portion *a* of the table top is pushed inward.

100 This moves the flap *e* until it passes down the slide *f* and on continuing the motion, the runners *c* pass under the top *a.1*, and the leaf *e* slides slowly down the bevels *i* into the level beneath the table. The other portion *a.1* of the top is then pushed inward 105 until the parts return to the position shown at Fig. 1.

110 It will be understood that the particular method of carrying out the invention just described is given merely by way of example, as the construction may be varied with-

in the scope of the appended claims without departing from the principle of my said invention.

What I claim and desire to secure by Letters Patent of the United States of America is:—

1. In an expanding table, the combination of a frame carried by the legs, the said frame having side rails, a top divided into 10 two sections, means for enabling each of the said sections to slide with respect to the side rails so that the said sections can be brought together or separated, means for limiting the sliding action of the said sections, a loose leaf, a recess in the side rails of sufficient size to enable the loose leaf to rest within the same and to come below the sectional top of the table, runners attached at one end to one of the sections of the top, 20 means beneath the other section of the top for supporting the said runners, recesses in the said runners, to receive the additional leaf and to allow it to rest beneath the sectional top of the table, inclined surfaces at 25 the ends of the cut away portions of the runners remote from the top section to which the said runners are attached, and inclined surfaces to the cut away portions of the side rails facing in an opposite direction to the inclines on the cut away portions on the runners, all for the purposes set forth.

2. In an expanding table, the combination of a frame carried by the legs, side rails to the said frame, a top divided into two sections, 35 rabbeted portions coming below the two sections of the top, grooves in the side rails and the legs for the reception of the said rabbeted portions for enabling the sections of the top to be brought together or 40 separated, means for limiting the sliding action of the said sections, a loose leaf, a recess in the side rails of sufficient size to enable the loose leaf to rest within the same and to come below the sectional top of the 45 table, runners attached at one end to one of the sections of the top, a bridge beneath the other section of the top for supporting

and guiding said runners, recesses in the said runners to receive the additional leaf and to allow it to rest beneath the sectional top 50 of the table, inclined surfaces at the ends of the cut away portions of the runners remote from the top section to which the said runners are attached, and inclined surfaces to the cut away portions of the side rails 55 facing in an opposite direction to the inclined surfaces on the cut away portions on the runners, all for the purposes set forth.

3. In an expanding table, the combination of a frame carried by the legs, side rails to 60 the said frame, a top divided into two sections, rabbeted portions coming below the two sections of the top, grooves in the side rails and the legs for the reception of the 65 said rabbeted portions for enabling the sections of the top to be brought together or separated, means for limiting the sliding action of the said sections, a loose leaf, a recess in the side rails of sufficient size, to enable the loose leaf to rest within the same 70 and to come below the sectional top of the table, runners attached at one end to one of the sections of the top, a bridge beneath the other section of the top for supporting and 75 guiding the said runners, recesses in the said runners to receive the additional leaf and to allow it to rest beneath the sectional top of the table, inclined surfaces at the ends of the cut away portions of the runners remote 80 from the top section to which said runners are attached, and inclined surfaces to the cut away portions of the side rails facing in an opposite direction to the inclined surfaces 85 on the cut away portions on the runners, and means beneath the loose leaf for preventing the lateral displacement thereof, all substantially as described, and for the purposes set forth.

In witness wheroft I have hereunto affixed my signature this 29th day of June 1917.

FRANK WILLIAM SYRED.
